UNITED STATES PATENT OFFICE

ERNEST JOHNSTON, OF LOVELAND, COLORADO

DESIGN FOR A BUILDING

Application filed March 16, 1931. Serial No. 39,101. Term of patent 14 years.

To all whom it may concern:

Be it known that I, ERNEST JOHNSTON, a citizen of the United States, residing at Loveland, in the county of Larimer and State of Colorado, have invented a new, original, and ornamental Design for a Building, of which the following is a specification, reference being had to the accompanying drawings, forming part thereof.

In the drawings—

Fig. 1 is a plan view of my building;
Fig. 2 is a side elevation of the same; and
Fig. 3 is an end elevation of the same.

I claim:

The ornamental design for a building substantially as shown.

ERNEST JOHNSTON.
